UNITED STATES PATENT OFFICE.

READER M. LIGHT AND GEORGE V. WILSON, OF BERRIEN SPRINGS,
MICHIGAN.

DESIGN FOR A LANTERN.

SPECIFICATION forming part of Design No. 27,022, dated May 4, 1897.

Application filed March 16, 1897. Serial No. 627,884. Term of patent 14 years.

To all whom it may concern:

Be it known that we, READER M. LIGHT and GEORGE V. WILSON, citizens of the United States, residing at Berrien Springs, 5 in the county of Berrien and State of Michigan, have invented and produced a certain new and original Design for a Lantern; and we do declare the following to be a full, clear, and exact description of the invention, such 10 as will enable others skilled in the art to which it appertains to make and use the same.

Our invention relates to a new and original design for a lantern; and it consists of a lantern of the configuration and ornamentation shown in the accompanying drawing, in which 15 we have illustrated our invention in perspective.

The leading features of our design consist 20 in the hollow jacket 2, of cylindrical form, provided with an annular supporting-flange 3 and a tapering top 4, above which is a chimney 5 and a frame of the form shown. This

jacket contains a glass reservoir 6 and is provided on opposite sides and on the tapering 25 portion with vertical rows of apertures, through which may be seen the contents of the glass reservoir, and which form distinctive contrasting colors which are very pleasing to the eye. This construction, while enabling a person to observe the contents of 30 the reservoir, also provides against accidental breakage.

Having thus described our invention, what we claim as new and original, and desire to 35 secure by Letters Patent of the United States, is—

The design for a lantern, as herein shown and described.

In testimony whereof we hereunto affix our 40 signatures in presence of two witnesses.

READER M. LIGHT.
GEORGE V. WILSON.
